HENRY S. NEWLIN, OF JERSEY CITY, AND WILLIAM E. DATE, OF EAST ORANGE, NEW JERSEY; SAID NEWLIN ASSIGNOR TO THE M. W. KELLOGG COMPANY, OF NEW YORK, N. Y., A CORPORATION OF DELAWARE

METHOD AND APPARATUS FOR ROLLING TUBULAR ARTICLES

Application filed October 8, 1927. Serial No. 224,892.

This invention relates to a load equalizer and more particularly to a method and means for equalizing the load in a rolling machine employing inner and outer rolls.

5 In the operation of rolling, it is often desirable, as for example in the rolling of large cylindrical bodies of tubular form, to employ both inner and outer rolls. In rolling small cylinders the work is ordinarily all 10 done by the outer roll and its motor, the inner roll and motor idling with no current on the motor. When rolling larger cylinders where it is desirable to use both rolls the difficulty is encountered that as the thickness of the cylinder 15 is constantly decreased the inside peripheral speed of the cylinder is constantly increased. In order to meet this condition and to keep both rolls doing effective work, the speed of the inside roll must be increased 20 so as to keep the peripheral speed thereof synchronized with the inside peripheral speed of the cylinder. Unless this is done there will be a tendency for the rolls to exert a tearing action upon the metal and to set up 25 stresses in the walls of the article produced. At the same time the load will be unequally distributed between the motors operating the respective rolls.

It is accordingly the aim of this invention 30 to provide a method and means by which the load may be equalized between two motors, the speed of one of which is constantly increasing.

A further object of the invention is to provide 35 a means for constantly increasing the speed of one of two motors bearing a cumulative load in order to bring about equal rolling on both the inside and outside of a cylinder.

40 Others objects and advantages of the invention will be apparent from the following detailed description taken in conjunction with the accompanying drawing, in which:

45 Fig. 1 is a more or less diagrammatic view in side elevation of a rolling mechanism for rolling tubular articles from hollow cylindrical billets or ingots.

Fig. 2 is a vertical section on the line 2—2 50 of Fig. 1 illustrating the relation of the

rolls to the cylindrical body being rolled and

Fig. 3 is a diagrammatic showing of the layout of the electric circuits used in controlling the operation of the roll-actuating motors. 55

As shown in the drawing a hollow billet or ingot 10 is placed upon the upper roll 11 and the lower roll 12 is brought into contact with the outside of the billet 10. The roll 12 is connected through suitable gearing to a motor M^1 which we propose to operate as a constant speed motor. The roll 11 is connected through suitable gearing to a motor M^2 . It will be apparent that when 60 pressure is applied to the rolls the hollow billet 10 will expand on its diameter and that as its walls become thinner its inside peripheral speed will tend to approach that of the outside. Therefore, if the roll 12 is rotated 65 at a constant speed, the speed of the upper roll 11 will have to be constantly increased. To accomplish this and to equalize the load between the motors M^1 and M^2 we provide an automatic control mechanism as is indicated diagrammatically in Fig. 3. In this figure, M^{10} and M^{20} indicate the armatures of the motors M^1 and M^2 respectively. F^1 and F^2 represent the fields of these motors. 70 75

At 13 and 14 are shown plungers which 80 act respectively as the solenoid cores for the coils C^1 and V^1 on the one hand and the coils C^2 and V^2 on the other. The coils V^1 and V^2 are connected across lines L^1 and L^2 leading to a suitable source of current supply as indicated at 15 and 16 and the flow of current through such coils is controlled by means of the rheostats R^1 and R^2 . It will, therefore, be seen that the coils V^1 and V^2 function as voltage coils and compensate for any variation in the line voltage. Since with constant power output any drop in voltage will be accompanied by an increase in amperage, it will be seen that the magnetic pull on the solenoid cores 13 and 14 will be balanced so 85 long as the power or wattage applied to each motor is the same, because any weakening of one of the voltage coils V^1 or V^2 due to a drop in voltage will simply mean the strengthening of the corresponding current 90 95 100

coil C¹ or C², and, therefore, result in the same magnetic pull on the solenoid core. Since with this arrangement both voltage and amperage are taken into consideration the respective pairs of coils C¹ and V¹ or C² and V² represent watt coils or a true measure of the electrical energy passing through them.

The solenoid cores or plungers 13 and 14 are connected to the respective arms of the rock-lever device 17 fulcrumed at 18 and having switch arms 19 and 20. The arm 19 is arranged to close a circuit by means of the contacts 21 and 22 through one field of the 15 split field motor M³, and the arm 20 is arranged to close a circuit by means of the contacts 23 and 24 through the other field of the split field motor M³.

The motor M³ is connected to operate a 20 field rheostat R³ which is adapted to strengthen or weaken the field F² of the variable speed motor M². The motor M², having shunt characteristics, responds to any change in field strength with a resulting increase or 25 decrease in speed. A hand operated rheostat R⁴ is also provided for adjusting the speed of the constant speed motor to any desired predetermined point. In other words, this constant speed motor can be set for any 30 number of revolutions up to its weakened field speed.

As illustrative of the operation of the apparatus, let us assume that a hollow cylindrical blank or billet has been placed in the 35 rolls. The current is turned on and the motors caused to come to approximately the same speed as determined by the constant speed setting of the motor M¹. If during the course of the rolling operation the motor M² is lagging behind the motor M¹ in speed, then it is evident that more current will be flowing 40 through the motor M¹. This will cause the magnetic pull of the coils V¹ and C¹ on the solenoid core 13 to exceed that exerted by the coils V² and C² on the solenoid core 45 14, thereby causing the rock lever device 17 to turn on its fulcrum at 18 and close the contacts 23 and 24 and through them the circuit through one field of the motor M³. The 50 motor M³ will then operate to change the setting of the rheostat R³ and cause the speed of the motor M² to increase until the proper speed setting is reached. Should the motor M² tend to assume more than its share of the 55 load, then the reverse will take place.

If it is desired that one of the motors M¹ and M² should assume more of the load than the other, this may be accomplished by suitably adjusting the rheostats R¹ and R².

While the invention has been described with particular reference to the use of direct current motors it will be understood that with very slight modifications of the wiring 65 and circuit connections it may be applied to

alternating current induction motors of the wound rotor type.

It will be further understood that instead of continuously increasing the speed of one of the motors while maintaining the other constant the circuit arrangement may be such that the speed of one of the rolls is maintained constant while the other is progressively decreased.

It is also to be understood that various other modifications and changes may be made without departing from the scope of the invention, which is not to be deemed to be limited other than as indicated by the appended claims.

What we claim is:—

1. The method of equalizing the load between two motors the speed of one of which varies continuously, which comprises tying the said motors together through a differential load control device consisting of a pivoted bar member having contact means at either end, magnets connected with either end of said bar and energized by the respective motor circuits, said magnets when unequally energized being adapted to turn said pivoted member to make contact with a rheostat member connected to each motor circuit and causing the speed of one motor to increase until both magnets are energized equally.

2. In a rolling mill, rolls for engaging a tubular blank and applying rolling pressure to the inner and outer surfaces of said blank, motors for operating said rolls, and means for controlling the relative speeds of said rolls comprising magnets connected respectively to the respective motor circuits and responsive to differences in power input to the respective motor circuits, said magnets being connected to a current-controlling mechanism adapted to vary the current supply to one of said motors.

3. In a rolling mill, rolls for engaging a tubular blank and applying rolling pressure to the inner and outer surfaces of said blank, motors for operating said rolls, means for maintaining the speed of one of said rolls constant, and means for continuously varying the speed of the other to maintain the peripheral speeds of the two rolls synchronized with the peripheral speeds of the respective surfaces of the blank with which they are in contact, said means comprising solenoids responsive to difference in power input to the respective motors and actuating a motor-controlled rheostat varying the current input into the motor actuating the variable speed roll.

In testimony whereof, we have signed our names to this specification this fourth day of October, 1927.

HENRY S. NEWLIN.
